DESIGN FOR A STOKER CABINET OR THE LIKE

Harold Van Doren and Donald E. Dailey, Toledo,
Ohio, assignors to Kingston Products Corpora-
tion, Kokomo, Ind., a corporation of Indiana

Application January 16, 1941, Serial No. 98,117

Term of patent 7 years

To all whom it may concern:

Be it known that we, Harold Van Doren and Donald E. Dailey, citizens of the United States, residing at Toledo, in the county of Lucas and state of Ohio, have invented a new, original, and ornamental Design for a Stoker Cabinet or the like, of which the following is a specification, reference being had to the accompanying drawing, forming part thereof.

Figure 1 is a front perspective view of a stoker cabinet or the like, showing our new design;

Figure 2 is a rear perspective view thereof on a slightly reduced scale;

Figure 3 is a fragmentary sectional view taken on line 3—3 of Figure 1; and

Figure 4 is a fragmentary sectional view on the line 4—4 of Figure 1.

We claim:

The ornamental design for a stoker cabinet or the like, as shown.

HAROLD VAN DOREN.
DONALD E. DAILEY.
